**AIR-VACUUM DRYER UNIT FOR ATTACHMENT
TO A STEAM GARMENT PRESSING MACHINE**

Joseph D. Pellerin, East Norwalk, Conn., assignor to
Rema Corporation, Norwalk, Conn., a corporation of
Connecticut

Application May 13, 1955, Serial No. 35,974

Term of patent 14 years

(Cl. D49—1)

Fig. 1.

Fig. 2.

Fig. 3.

Fig. 1 is a perspective view of an air-vacuum dryer unit for attachment to a steam garment pressing machine showing my new design;

Fig. 2 is a top plan view, and

Fig. 3 is an end elevation looking from the left of Fig. 1.

The end not shown is substantially plain, and both sides are the same.

I claim:

The ornamental design for an air-vacuum dryer unit for attachment to a steam garment pressing machine, substantially as shown and described.
